United States Patent Office

Des. 221,944
Patented Sept. 21, 1971

221,944

ANDIRON OR THE LIKE

Carl Coleman Strickland, Wendell, N.C. 27591

Filed Jan. 30, 1970, Ser. No. 21,168

Term of patent 14 years

Int. Cl. D23—03

U.S. Cl. D23—102

Fig. 1

Fig. 2

Fig. 3

Fig. 4

FIG. 1 is a front plan view of the andiron or the like, showing my new design;

FIG. 2 is a top rear perspective view thereof;

FIG. 3 is a bottom rear perspective view thereof; and

FIG. 4 is a bottom front perspective view thereof. The letter s is shown in broken lines in FIGS. 1, 2, 3 and 4 for illustrative purposes only.

I claim:

The ornamental design for an andiron or the like, as shown and described.
